INVENTOR.

William J. Fansay

UNITED STATES PATENT OFFICE

1,956,660

HAIR CURLER

William J. Tansey, San Francisco, Calif.

Application April 24, 1933, Serial No. 667,552

5 Claims. (Cl. 132—31)

The present invention relates generally to improvements in hair curlers, and especially to curlers adapted for use with both short and long hair.

5 It is the primary object of the present invention to provide an efficient, non-clogging, and ventilated curler that is light of weight, and adapted for use in setting the various types of coiffure now in vogue.

10 Another object of the invention is to provide a device of the class described, that is completely self-contained and that may be employed without the use of hair pins, crimpers and like fastening elements.

15 Another object of the invention is to provide a curler wherein curls or waves of different size may be formed, and one that embodies means for releasing the curler from the hair without snarling or disarranging the curl set in the hair.

20 A further object of the invention is to provide a device of the class described, wherein, when the hair is wound thereon, it will be rapidly dried by the application of the usual dryers, without causing any discoloration or staining of said hair.

25 In the accompanying drawing:—

Figure 1 is a side elevation of the device showing the ventilated curler and rolling iron in separated relation;

Figure 2 is a longitudinal section of the ventilated curler showing the rolling iron gripping both the hair and the curler;

Figure 3 is a plan view of the curler per se showing the fastening yoke and ventilating orifices therein;

Figure 4 is a side elevation of the device partly in section, illustrating the method employed in adjusting the fastening yoke of the curler; and

Figure 5 is an enlarged transverse section of the rolling iron jaws taken on the line 5—5 in Figure 4.

40 The instant invention is an adaptation of an improved form of the device shown in my allowed application, Serial No. 630,483, filed Aug. 26, 1932 for "Hair curlers", allowed, Nov. 18, 1932.

45 Applicant is aware of the fact that there have been many types of hair wave forming devices for use in the curling of hair, and particularly for use in forming what is commonly known, as the long bob roll curls. These devices, however, in 50 most instances are difficult to manipulate, heavy upon the head of the user and consequently uncomfortable. Said devices are also easily de-ranged, thus necessitating the employment of rubber bands, hair-pins and the like, to further 55 secure the hair upon the curler; and entailing

increased labor on the part of the operator. With applicant's device, the hair is quickly wound upon the curler through the manipulation of the rolling iron element, after which said element is withdrawn from the curler, pulling the fastening 60 yoke into place, as fully illustrated in Figure 4.

In the description of the preferred form of my invention, as disclosed in the drawing, the various mechanisms include broadly, a rolling iron 6; ventilated curler 7; fastening yoke 8; and loosening mechanism 9.

The rolling iron 6 is provided with a male jaw 10 and a female jaw 11 secured together by means of a rivet 12, as clearly shown in Figures 1-2 and 4, and said members are drawn together or spread 70 apart in a scissor like manner by means of handles. The male jaw 10 is provided with a lip 13 protruding at right angles to said jaw 10, and the functions of said lip will be more fully hereinafter described. The outer end 14 of the female 75 jaw 11 is tapered and substantially convexo-concave in transverse cross section, Figure 5, so that it may readily grip the cylindrical surface of the ventilated curler 7, and the hair 15, as illustrated in Figure 2. The tapered end 14 is provided primarily to facilitate the withdrawal of the rolling 80 iron 6 from the hair 15 without disturbing the set of the curl.

The ventilated curler 7 is formed from a tubular member 16, and is provided with a plurality 85 of perforations or orifices 17 to permit the circulation of air to the hair wound around the curler, as illustrated in Figure 2. A slot 18 is provided in the left hand end of the tubular member 16, and said slot is cut through both walls of 90 the tubular member 16 in such a manner that the fastening yoke 8 will remain stationary after being inserted within the slot 18. The right hand end of the member 16 is provided with a pair of elongated slots 19, acting as sliding bearings for 95 the fastening yoke 8, as shown in Figures 1-2 and 4.

The fastening yoke 8 is provided with a pivot 20, passing through the elongated slots 19 of the curler 7, and welded in a suitable manner to 100 the hubs 21 and 22 of the resilient wire 23, as shown in Figures 1 and 3.

Securely mounted on the inner wall of the member 16 is the loosening mechanism 9 composed of a resilient clamp 24, having one leg 105 of the same passing outwardly through the aperture 25 and thence extending in an arcuate manner alongside the outer face of the curler 7.

The curler 7 is placed against the extreme end 110 of the hair to be treated, and the rolling iron 6

is inserted into said curler in such a manner that the female jaw 11 will clamp the hair against the outer face of the curler 7, in the manner shown in Figure 2. The fastening yoke 8 is then 5 allowed to fall back against the outer part of the rolling iron 6 and is held in this position by the fingers of the operator. The male jaw 10 passes within the curler in the manner shown in Figure 2, and co-acts with member 11 in exerting 10 pressure to hold the curler 7 and hair 15 in rigid alinement. The rolling iron 6 is now rotated and the hair 15 is evenly wound about the curler 7 and over the loosening mechanism 9, till a roll of the desired amount of hair is obtained. The 15 operator now relaxes control over the fastening yoke 8, and proceeds to turn same over the hair, at the same time pulling said yoke into the slot 18, as shown by directional arrows in Figure 4. When the small end 26 of the yoke is opposite 20 the slot 18, pressure is removed from the rolling iron 6 and the female jaw 11 releases its grip upon the hair 15, and the rolling iron 6 may now be withdrawn from the curler 7. While withdrawing, the lip 13 of the male jaw 10 engages 25 the pivot member 20 and pulls the small end 26 of the resilient wire 23 into the slot 18. After the curl has had time to set, the operator grasps the small end 26 of the yoke 8, pulling same clear 30 of the slot 18 and thus releasing the hair. The hair having been released by the yoke, slightly unwinds, due to the pressure exerted by the loosening mechanism 9. The inside diameter of the curl now being larger than the diameter of the curler, said curler is readily slipped out of 35 the curl, without snarling or disarranging said curl.

I claim and desire to secure by Letters Patent of the United States the following:—

1. A device of the class described comprising

40

80

a cylindrical curler, a resilient yoke pivotally positioned thereon, and resilient means co-acting with said curler for loosening hair curled thereabout.

2. A device of the class described comprising a cylindrical curling element, a resilient yoke pivotally positioned thereon and slidably relative thereto, resilient means associated with said curler for loosening hair curled thereabout, and means for locking said yoke relative to said 85 curler.

3. A device of the class described comprising, in combination, a cylindrical curling element, a resilient yoke pivoted thereon and slidably relative thereto, locking means carried by one end 90 of said curler and adapted to receive the free end of said yoke, and a rolling iron insertable onto said cylindrical curling element and having jaws adapted to grip the same.

4. In a device of the class described, the combination with a cylindrical curling element, said element having a pivoted yoke arranged thereon and adapted to slide relative thereto, locking means carried by one end of said curler and adapted to receive the free end of said yoke to 100 clamp strands upon said curler, of a rolling iron means associated with said curler and embodying gripping jaws adapted to grip the curler and cause rotational motion to be imparted thereto to form the curl. 105

5. In a curling device of the class described, a cylindrical curling element, a resilient yoke pivoted thereon and having its pivoted end slidable therein, slots formed in the opposite end of said curling element to receive said yoke, means for drawing the free end of said yoke into said slots to lock the same on said element, and means for releasing the same from its locked position. 110
